ADJUSTING DEVICE FOR CYLINDER
GRINDERS

Fred M. Kern, Detroit, Mich., assignor, by mesne assignments, to The Carborundum Company, Niagara Falls, N. Y., a corporation of Pennsylvania

Application February 3, 1928, Serial No. 251,552

6 Claims. (Cl. 51—184.3)

This invention relates to a grinding device adapted to lap or grind the bore of cylinders or cylindrical openings and more particularly a device of this character in which a plurality of abrasive members are mounted on a supporting head or body, so that the same can be adjusted radially thereon for adapting the diameter of the tool to the size of the opening which is to be ground.

- 10 In grinding devices of this character as heretofore constructed, it has usually been necessary to disconnect the grinding device from the driving mechanism in order to gain access to the mechanism whereby the position of the grinding stones or abrasive members on the supporting body were adjusted which not only interrupted the operation of the machine but was also attended with inconvenience and increased cost in doing the work in hand.
- 15 It is the object of this invention to provide means for adjusting the position of the abrasive members from the exterior of the tool so as to avoid the necessity of dismounting the same, and more particularly an adjusting device having this capacity which permits of effecting this adjustment on grinding devices of a type already in use and thereby adapting this adjusting device to such tools without requiring any material structural alteration in the same.
- 20 In the accompanying drawings Fig. 1 is a side elevation of a grinding device equipped with the improved form of adjusting mechanism for the abrasive members.

Figure 2 is a longitudinal section of the same.

- 25 Figures 3, 4, and 5 are cross sections taken on the correspondingly numbered lines in Fig. 2.

In the following description the same reference characters indicate like parts in the several figures of the drawings:—

- 30 The adjusting mechanism is applicable to grinding devices which may vary to some extent in the details of construction and the grinding devices shown in the accompanying drawings may therefore be regarded as merely typical of one form of such device which is suitable for use in connection with the present invention.

In its general organization the grinding device shown in the accompanying drawings, is constructed as follows:—

- 35 The numeral 10 represents a supporting head or body having a longitudinal bore 11 and a plurality of transverse guide openings 12. Within the longitudinal bore are arranged two opposed adjusting cones 13, 14 arranged respectively in the upper and lower parts of this bore and ad-

justably connected with each other by means of a screw 15, the head 16 at the upper end of which bears against an upwardly facing shoulder 17 on the upper cone while the threaded lower end 18 of this groove engages with the lower cone 14. Upon tightening this screw, the cones approach each other, and upon loosening this screw the cones are spread apart by means of spring 19 surrounding this screw and bearing at its opposite ends against these cones, as shown in Fig. 2. 10

Surrounding the supporting head or body is an annular set of abrasive carriers, each of which is mounted on the supporting head and adjusted radially thereon by means of the cones. Each of these carriers in the form shown in the drawings, 15 comprises a longitudinal supporting bar or holder 20 which is provided on its outer side with one of the abrasive members or stones 21, while its inner side is provided with a pair of inwardly projecting guide pins 22 which slide in a pair of 20 these guide openings 12 in the supporting head and engage at their inner ends with the conical surfaces of the two cones on the supporting head.

Each of these carriers is yieldingly held in its innermost position by a spring device consisting 25 preferably of a wire spring 23 secured to the exterior of the supporting head and bearing at its opposite ends against the guide pins 12 of the respective carrier so that these pins are always maintained in engagement with the tapering surfaces of the cones. 30

At its upper end the supporting body is provided with an upwardly projecting tubular extension 24 which latter is provided on its opposite sides with bayonet slots 25 one of which is shown 35 in Fig. 1.

Ordinarily the upward extension 24 of the supporting head is connected directly with a driving spindle whereby the tool is rotated and also reciprocated in the cylindrical hole or bore of the 40 cylinder which is being ground and in such an installation it is necessary to dismount the grinder whenever access is required to the head 16 of the adjusting bolt for expanding or contracting the several abrasive carriers as the work of grinding progresses. Instead, however, of using an ordinary driving spindle a special form of driving spindle is used in the present case and adjusting means are associated with this spindle and the cone adjusting screw which permits of adjusting 45 the position of the abrasive members from the exterior of the spindle without requiring the tool to be disconnected from the spindle. 50

For this purpose the driving spindle in the present case consists of an upper solid section 55

26 and a lower tubular section 27 which latter is connected at its lower end with the tubular extension on the supporting head by means of an universal joint in order to permit the grinding device to play laterally relatively to the driving spindle and adapt itself to the surface which is being ground. In its preferred form this universal joint consists of a spherical knuckle 28 arranged on the exterior of the tubular spindle section 27 at the lower end thereof and arranged within the bore of the head extension 24, and provided on its opposite sides with coupling pins 29, each of which engages with an undercut seat 30 on the inner part of one of the bayonet slots 15 25, as shown in Fig. 1.

Owing to the direction of rotation of the driving spindle being toward the closed end of this bayonet slot these parts always remain coupled, while the tool is in operation, but when it is desired to uncouple these parts it is only necessary to move the grinding device forwardly independently of the spindle a distance sufficient to permit the coupling pins 30 to be disengaged from the bayonet slots above referred to.

25 The upper and lower sections of the spindle are preferably connected with each other by means of a screw joint 31 as shown in Fig. 2 and the upper section is adapted to be connected with any means whereby the same may be driven 30 either manually or by power. The upper part of the bore of the lower spindle section 27 is of comparatively large diameter and the lower part of this bore of relatively smaller diameter, thereby forming an upwardly facing internal shoulder 35 32 within the lower spindle section which is preferably of spherical form, as shown in Fig. 2.

The means whereby the cone adjusting screw 40 may be turned from the exterior of the driving spindle for adjusting the abrasive members are preferably constructed as follows:—

Arranged within the enlarged upper bore of the lower spindle section is an adjusting head 33 which is preferably hollow or cup-shaped and provided on its underside with a spherical surface 34 which engages with the shoulder 32 of the lower spindle section and therefore in effect forms a ball and socket joint between this adjusting head and the spindle section. From the lower side of this adjusting head a hollow or tubular neck 35 projects downwardly and is provided at its lower end with an opening 36 which is square or of other suitable rectangular form, the edge of this opening being comparatively narrow or tapered, as shown at 37 in Fig. 2. 55 This adjusting head is adapted to be rotated together with the neck 35 and this rotary movement is transmitted to the adjusting screw 15 by means of an adjusting rod 38, the upper end of which is of square or rectangular form in cross-section, as shown in Fig. 5, and fits into the opening 36 so that these parts are compelled to turn together and still permit the shifting rod to move lengthwise relatively to the neck 35. At its lower end the adjusting rod 38 is connected 60 by means of a universal joint with the upper end of the adjusting screw 15, this being preferably accomplished by means of a transverse pin 39 secured to the lower end of the adjusting rod 38 and projecting loosely at its opposite ends into openings 40 formed in a pocket 41 in the top of the screw head 16.

Surrounding the upper enlarged part of the tubular spindle section is an adjusting sleeve 42 which is provided with an adjusting pin 43 projecting inwardly through a circumferential slot

44 in the adjacent part of the tubular spindle section and adapted to engage with one or another of an annular row of teeth 45 on the upper end of the adjusting head 33. The slot 44 is sufficiently wide to permit the adjusting sleeve 5 42 to be raised and lowered the required extent for engaging and disengaging the adjusting pin 43 with one or another of the teeth 45, and this slot is also of sufficient length circumferentially of the tubular spindle section to permit of turning or rotating the adjusting sleeve for turning the same circumferentially to an extent equal to the space between one or more teeth as desired. Upon engaging the adjusting pin 43 with a tooth of the adjusting head at one end of the 10 slot 44 and then moving this pin toward the opposite end of the slot by means of the sleeve 42, it will result in turning the adjusting head 33 in one direction, which motion upon being transmitted by the adjusting rod 38 to the screw 20 15 will cause the cones to be moved lengthwise relatively to each other in one direction, while upon engaging the adjusting pin 43 with one of the teeth 45 adjacent to the opposite end of the slot 44 and then moving the sleeve 42 in the 25 reverse direction it will result in turning the adjusting screw 15 in the opposite direction. It is therefore possible by these means to adjust the cones lengthwise relatively to each other by steps which can be either forward or backward and 30 varying in length for the purpose of varying the diameter of the abrasive surfaces of the grinding device to suit the requirements of the particular work which is being operated on.

During this work the adjusting head and its 35 neck 35 are free to tilt or rock laterally to a limited extent and the adjusting rod 38 is also free to swing laterally by reason of the universal connection with the adjusting screw 15 and the engagement of its square sided upper part with 40 the narrow edge 37 of the adjusting neck 35, thereby avoiding cramping of any of the parts and permitting free working of the adjusting mechanism in all the various positions which these parts are likely to assume when in use. 45 The possibility of any cramping action between the adjusting rod 38 and the lower end of the tubular neck 35 is further prevented by arranging the narrow edges 37 of the opening 36 50 transversely in line with the axis of the pins 29 which form part of the universal connection between the driving spindle and the head of the abrasive device, as shown in Figs. 1 and 2.

In order to hold the adjusting head 33 against its seat 32 on the tubular driving spindle section and maintain the same in its proper position relatively to the parts with which it cooperates and still permit the same to move with the required degree of freedom for accomplishing its purpose, retaining means are provided which 60 preferably consist of a disk 46 engaging with the inner side of the bottom of the head 33 and a retaining pin 47 secured at its upper end to the lower end of the solid section 26 of the driving spindle while the lower end of this retaining pin 47 bears against the upper side of the retaining pin 46 adjacent to the axis of the adjusting head 33, as shown in Figs. 2 and 4.

It will thus be apparent that by means of this mechanism it is possible to effectively drive the grinding device and also to adjust the diameter of the grinding device easily and conveniently from the exterior of the tool without requiring the same to be dismounted or interrupting the 70 75

working of the same for any undue length of time.

Moreover this mechanism for driving and adjusting the grinding device permits of readily and efficiently using grinding devices which have heretofore been unprovided with external adjusting means with the same facility as grinding devices which have been especially constructed to permit of adjustment from the exterior of the same. Furthermore, all the parts of this adjusting device are of sturdy construction and well-protected by reason of their location within the interior of the mechanism where they are not likely to become injured and rendered inoperative.

I claim as my invention:

1. A grinding device comprising a supporting head; a plurality of abrasive carriers movable radially on said head; opposed cones slidable lengthwise of said head and engaging with the inner parts of said carriers; a rotary adjusting screw connecting said cones; a driving spindle having a tubular lower section operatively connected with said supporting head; and means for turning said adjusting screw including a rotary adjusting head mounted in said tubular section and operatively connected with said screw and provided with an annular row of teeth; an adjusting sleeve surrounding said tubular section and having a coupling pin adapted to engage with one or another of said teeth for turning said adjusting head, and means for holding said adjusting head against rising in said tubular section, comprising a disk engaging with said head, and a retaining rod secured at its upper end to the upper part of said spindle and bearing at its lower end against said disk.

2. A grinding device comprising a supporting head; a plurality of abrasive carriers movable radially on said head; opposed cones slidable lengthwise of said head and engaging with the inner parts of said carriers; a rotary adjusting screw connecting said cones; a driving spindle having a lower tubular section operatively connected at its lower end with said supporting head and provided at its upper end with an upwardly facing internal shoulder; a rotary adjusting head resting on said shoulder and having an annular row of teeth and a depending tubular neck the lower end of which has an angular opening; a coupling rod connected with said adjusting screw and having an upper angular part engaging with said angular opening; and an adjusting sleeve surrounding said tubular section and having an inwardly projecting pin adapted to engage with one or another of said teeth.

3. A grinding device comprising a supporting head; a plurality of abrasive carriers movable radially on said head; opposed cones slidable lengthwise of said head and engaging with the inner parts of said carriers; a rotary adjusting screw connecting said cones; a driving spindle having a tubular lower section operatively connected with said supporting head; and means for turning said adjusting screw including a rotary adjusting head mounted in said tubular section and operatively connected with said screw and provided with an annular row of teeth; an adjusting sleeve surrounding said tubular section and having a coupling pin adapted to engage with one or another of said teeth for turning said adjusting head, said adjusting head being free to turn and tilt in said tubular section.

4. A grinding device comprising a supporting head; a plurality of abrasive carriers movable

radially on said head; opposed cones slidable radially on said supporting head and engaging with the inner parts of said carriers; a rotary adjusting screw having a head at its upper end engaging with one of said cones and a screw thread on its other end engaging with the other cone; a driving spindle having a lower tubular section provided with an upwardly facing internal shoulder and an adjusting slot in its side above said shoulder; a universal joint connecting the lower end of said tubular section with the upper end of said supporting head; and means for rotating said adjusting screw from the exterior of said spindle including a hollow adjusting head arranged within said tubular section and having a spherical underside resting on said shoulder, an annular row of upwardly projecting teeth, and a reduced tubular neck arranged within said tubular section and provided at its lower end with an angular opening the edge of which is narrow and arranged in line with said universal joint; a longitudinal coupling rod loosely connected at its lower end by a transverse pin with the head of said adjusting screw and having its upper end of angular cross section and engaging with said opening; an adjusting sleeve surrounding said tubular section and capable of rotary and longitudinal movement thereon; and an adjusting pin projecting inwardly from said sleeve through said adjusting slot and adapted to engage with one or another of said teeth.

5. A grinding device comprising a supporting head; a plurality of abrasive carriers movable radially on said head; opposed cones slidable radially on said supporting head and engaging with the inner parts of said carriers; a rotary adjusting screw having a head at its upper end engaging with one of said cones and a screw thread on its other end engaging with the other cone; a driving spindle having a lower tubular section provided with an upwardly facing internal shoulder and an adjusting slot in its side above said shoulder; a universal joint connecting the lower end of said tubular section with the upper end of said supporting head; and means for rotating said adjusting screw from the exterior of said spindle including a hollow adjusting head arranged within said tubular section and having a spherical underside resting on said shoulder, an annular row of upwardly projecting teeth, and a reduced tubular neck arranged within said tubular section and provided at its lower end with an angular opening the edge of which is narrow and arranged in line with said universal joint; a longitudinal coupling rod loosely connected at its lower end by a transverse pin with the head of said adjusting screw and having its upper end of angular cross section and engaging with said opening; an adjusting sleeve surrounding said tubular section and capable of rotary and longitudinal movement thereon; an adjusting pin projecting inwardly from said sleeve through said adjusting slot and adapted to engage with one or another of said teeth; a disk arranged with said hollow adjusting head and engaging with the bottom thereof, and a retaining rod secured at its upper end to the upper part of said spindle and engaging its lower end with the top of said disk.

6. A grinding device comprising a supporting head; a plurality of abrasive carriers movable radially on said head; opposed cones slidable radially on said supporting head and engaging with the inner parts of said carriers; a rotary adjusting screw having a head at its upper end engaging with one of said cones and a screw

thread on its other end engaging with the other cone; a driving spindle having a lower tubular section provided with an upwardly facing internal shoulder and an adjusting slot in its side above said shoulder; a universal joint connecting the lower end of said tubular section with the upper end of said supporting head; and means for rotating said adjusting screw from the exterior of said spindle including a hollow adjusting head 10 arranged within said tubular section and having a spherical underside resting on said shoulder, an annular row of upwardly projecting teeth and a reduced tubular neck arranged within said tubular section and provided at its lower end with an 15 angular opening, the edge of which is narrow

and arranged in line with said universal joint; a longitudinal coupling rod loosely connected at its lower end by a transverse pin with the head of said adjusting screw and having its upper end of angular cross section and engaging with said opening; an adjusting sleeve surrounding said tubular section and capable of rotary and longitudinal movement thereon; and an adjusting pin projecting inwardly from said sleeve through said adjusting slot and adapted to engage with one or another of said teeth, said adjusting head and shank being free to turn and tilt in said tubular neck. 5 10
